UNITED STATES PATENT OFFICE.

JAMES THOMAS DAVISON, OF WESTFIELD, MASSACHUSETTS.

BELT CUTTING AND TRIMMING MACHINE.

Application filed May 31, 1922. Serial No. 564,694.

To all whom it may concern:

Be it known that I, JAMES T. DAVISON, a citizen of the United States, and a resident of Westfield, in the county of Hampden and 5 State of Massachusetts, have invented new and Improved Belt Cutting and Trimming Machines, of which the following is a full, clear, and exact description.

This invention relates to improvements in 10 belt cutting and trimming machines, an object of the invention being to provide a machine of the character stated which will cut or trim a belt, strap or like device, the cut beginning at either side of the belt, or 15 either end of the belt, or between the ends of the belt, as may be desired.

A further object is to provide a machine 20 of the character stated, which is strong and durable, simple in construction and operation, and which greatly expedites and improves the cutting or trimming of belts and the like.

With these and other objects in view, the 25 invention consists in certain novel features of construction and combinations, and arrangement of parts, as will be more fully hereinafter described and pointed out in the claims.

In the accompanying drawings, 30 Figure 1 is a view in side elevation illustrating my improved machine.

Figure 2 is a sectional plan view on the line 2—2, of Figure 1.

Figure 3 is a view in end elevation.

Figure 4 is a view in transverse section on the line 4—4, of Figure 1.

1 represents a base or bed to which a frame 2 is rigidly fixed. This frame 2 extends longitudinally of the base 1 and provides two pair of parallel rails 3, 3 and 4, 4, respectively. The rails 3 and 4 are in vertical alignment and constitute guides for sliding blocks 5 and 6 respectively. These blocks 5 and 6 are made with recesses in 45 their upper and lower edges to receive the rails 3, 3 and 4, 4 respectively.

A vertically positioned knife, or cutting blade 8 is secured by screws 9 to the respective blocks 5 and 6 and this blade or 50 knife 8, is preferably provided with sharp cutting edges at both edges thereof to permit the knife to cut with equal facility in both directions of movement.

Belt supporting platforms 10 and 11 respectively are secured upon blocks 12 on 55 base 1 and have upwardly projecting flanges

13 at their side edges, against which a belt or the like can be positioned.

It will be noted that these platforms 10 and 11 are located at opposite sides of the 60 blade 8, or in other words, the blade 8 moves between the platforms 10 and 11 to sever a belt, or to trim a belt resting on either or both of the platforms.

The block 6 is provided with a screw 65 threaded opening 14 receiving a screw 15, the latter having suitable bearings at its ends in the frame 2 and at one end is provided with a pinion 16, which is driven by a gear wheel 17 on a short drive shaft 18, 70 and a crank arm 19 is secured on the shaft 18 to turn the latter. A suitable housing 20 encloses the gear 17 and pinion 16 as shown.

The operation is as follows:

A belt or other device to be cut, is placed on one, or both of the platforms 10 or 11 and the knife 8 is caused to move between the platforms to cut, or sever the belt. This movement of the knife, or blade, 80 is caused by the rotary motion of the screw 15 engaging the screw threaded opening 14 of block 6 and motion is imparted to the screw through the medium of the pinion 16, gear 17, shaft 18 and crank 19, as will 85 be readily understood.

Various slight changes might be made in the general form and arrangement of parts described without departing from my invention, and hence I do not limit myself to 90 the precise details set forth, but consider myself at liberty to make such changes and alterations as fairly fall within the spirit and scope of the appended claims.

I claim:

1. A machine of the character stated, comprising a support, two pair of rails on the support one above the other, a block slidably mounted between each pair of rails, a knife or blade connecting the blocks, a belt support adjacent to the blade, and means for sliding the said blocks.

2. A machine of the character stated, comprising a support, two pair of rails on the support one above the other, a block slidably mounted between each pair of rails, a knife or blade connecting the blocks, a belt support adjacent to the blade, flanges at both side edges of the belt support, and means for positively moving the blocks in 110 either direction on the rails.

3. A machine of the character described,

comprising a base, a frame on the base, two pairs of horizontal rails on the frame, all of said rails in the same vertical plane, blocks located between the pairs of rails and having recesses receiving the rails, a knife movably secured to the two blocks, a screw having rotary mounting in the frame and having screw threaded engagement with one of the blocks, a pinion on the screw, a drive shaft, a crank arm on the drive shaft, and a gear on the drive shaft meshing with the pinion.

4. A machine of the character described, comprising a base, a frame on the base, two pairs of horizontal rails on the frame, all

of said rails in the same vertical plane, blocks located between the pairs of rails and having recesses receiving the rails, a knife removably secured to the two blocks, a screw having rotary mounting in the frame and having screw threaded engagement with one of the blocks, a pinion on the screw, a drive shaft, a crank arm on the drive shaft, a gear on the drive shaft meshing with the pinion, a pair of belt supports located at opposite sides of the path of movement of the blade, and flanges at both side edges of said belt supports.

JAMES THOMAS DAVISON.
